UNITED STATES PATENT OFFICE.

EDWARD W. SCHUESSLER, OF BIRMINGHAM, ALABAMA.

SAFETY APPLIANCE FOR MINE CARS.

Application filed August 31, 1925. Serial No. 53,681.

My invention relates to a safety stop for mine cars and the like which is adapted to go automatically into operation, when a trip of cars or any car in a trip breaks loose on a grade, and prevent a run away down the track, which is the cause of so many serious mine accidents.

My present invention contemplates the provision, preferably on each car of a trip, of a hinged stop preferably adapted to have the couplings or haulage cable connected thereto so that the pull thereof will act to hold its free end up, but when the pull is relaxed the free end of the stop will drop and engage the track so as to hold the car or trip.

My invention further contemplates the provision of an automatic latch adapted to be controlled by trips in the track, which act to shift it into position to latch the stop element in raised position, while the car is being moved at the bottom or top of the slope, and to shift it reversely to release the stop for automatic operation, when the car again moves on to the incline.

My invention further comprises the novel details of construction and arrangements of parts, which in their preferred construction only are illustrated in the accompanying drawings, in which:—

Fig. 1 is a side elevation partly broken away of a mine car equipped with my invention.

Fig. 2 is an end view of Fig. 1.

Fig. 3 is a plan view showing the track and latch mechanism with the stop shown in dotted line.

Similar reference numerals refer to similar parts throughout the drawings.

In the embodiment of my invention illustrated in the drawings, I show my invention applied to an automatic safety stop to mine cars, though it may obviously be applied to other types of cars. The car as illustrated comprises a body 1 having a bottom 2 supported by cross axles 3 carrying wheels 4 which travel on the mine track rails 5 that are supported on cross ties 6. A bumper casting attached to the bottom forms a draw bar 7 having spaced perforated lugs or ears between which I pivotally mount, on the pin 8, a stop 9 which at its upper end has an extension 10 perforated and adapted to receive the coupling 11, which is typical of any connection between cars or of any haul-

age connection such as a cable, chain or rope. The end extension 10 has a flat face adapted to abut against a stop 12 integral with the draw bar. The lower end of the stop is pointed and shaped so that when the pull on its upper end is released or relaxed it will drop on the track and engage the road bed or cross ties so as to prevent the loose car or trip running back down the incline.

While the arrangement thus described is entirely practical and automatic in its action, it will be at once apparent that the stop is liable to give trouble after the mine car has passed off the incline and is being handled throughout the levels at the bottom of the mine or on the tipple. Under such conditions it is desirable that the stop shall be prevented from dragging on the track and interfering with the free movement of the car, and it is of course preferable that the mechanism to prevent this should be automatic in its action. To this end I have conceived the idea of providing a latch 13 formed of a square metal stop which is disposed transversely of the car opposite the inner end of the stop and adapted to slide in a guide frame 14 attached to the bottom of the car and provided with a pair of spaced aligning guides 15 and 16 which fit the latch pin close enough to prevent it rocking therein while leaving it free to move towards and from the stop 9. The outer end of the latch is bent down to provide a trip arm 17 and between the stop guides 15 and 16 the underside of the latch is provided with a shoulder 18. I mount a trip plate 19 at both ends of the inclined track, this plate being spike or otherwise secured to the cross ties or track bed preferably between the rails, and it comprises two relatively offset and reversely inclined guides 20 and 21 connected by a raised diagonal connecting guide 22. This trip is set so that it will engage the latch arm 17 and will first raise the latch by forcing the arm to ride up either incline and then will shift the latch according to the direction of the diagonal guide section 22. The trip is set with the diagonal guide disposed in the direction in which it is desired to shift the latch and since the latch should release the stop 9 while the car is traveling on an incline, it follows that the track trip should be set so as to throw the latch out, or into released position, as the car moves onto the incline, and to throw it in, or into

stop locking position, as the car moves off the incline at either top or bottom of the slope.

In operation, assuming that the latch is in its inner or stop holding position, it will be apparent that the stop 9 will be held away from the track and the car left entirely free for movement in any direction just as if it did not have an automatic safety stop, and in this position the shoulder 18 on the latch being engaged between the guides 15 and 16 will positively hold the latch against accidental disengagement. Assuming that the car is approaching an incline, the track trip will be set so as to receive the latch arm 17 on its inner inclined guide 20 which will act first to lift the latch until its shoulder 18 clears the bottom of the guides 15 and 16, then the outwardly disposed intermediate guide 22 will shift the latch outwardly to open position releasing the stop 9, and finally the latch arm as it rides down the outer incline 21 will be lowered until its shoulder 18 is again in position to engage the outer guide 15 only and to be held thereby so that it cannot accidentally be thrown in. The stop 9 is now free to drop to the track whenever the pull on the coupling or haulage connection relaxes and before the car runs off the other end of the incline another track trip will raise the latch, shift it in and drop it back into full line locked position, which will latch the stop in raised or inoperative position. The stops 12 will take the thrust and impact off the stops when they go into action and will save wear on the car proper.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is—

1. A safety mine car stop, comprising a draw bar having pivoted thereto a coupling element adapted at its outer end to connect to the car haulage means, and having its inner end overbalanced and adapted to drop

by gravity into engagement with the track when the pull on its outer end is relaxed, and a shoulder on the draw bar which the stop is adapted to engage as it goes into service.

2. In a safety mine car stop, the combination of a pivoted gravitating stop arm adapted to engage the track, of latch means to hold the stop in inoperative position, and track trip means to throw the latch.

3. In a safety mine car stop, the combination of a pivoted gravitating stop arm adapted to engage the track, latch means to hold the stop in an inoperative position, track trip means to throw the latch automatically, and means on the latch to lock it in either operative or inoperative position against accidental displacement.

4. In a safety car stop, a pivoted gravitating latch adapted to engage the track, means responsive to the haulage pull on the car to hold the stop in inoperative position, a latch transversely movable and also adapted to hold the stop in inoperative position, and track means to move the latch into and out of stop-engaging position.

5. In a safety car stop, a stop, means responsive to the haulage pull on the car to hold it in inoperative position comprising a shoulder, latch means with which the shoulder co-acts to prevent accidental movement of the latch, and track trips adapted to move the latch to disengage the shoulder from the guides and then to shift the latch into or out of operating position.

6. In a safety car stop, a draw bar rigidly connected to the bottom of the car, a bumper shoulder on the end of the car above said draw bar, a gravitating stop pivotally connected to said draw bar and provided with an end coupling element and between said coupling element and pivot point having an upturned shoulder adapted to co-act with said bumper element when the latch drops to operating position, the inner end of the stop being pointed and adapted to overbalance the outer end of the stop and to drop by gravity into track engaging position when the pull on its coupling end is relaxed.

In testimony whereof I affix my signature.

EDWARD W. SCHUESSLER.
